UNITED STATES PATENT OFFICE.

ELLIS R. BROCK, OF BAMBERG, SOUTH CAROLINA.

THREAD-BOARD CLEANER FOR SPINNING-MACHINES.

1,369,961.

Specification of Letters Patent.

Patented Mar. 1, 1921.

Application filed April 23, 1920. Serial No. 376,059.

To all whom it may concern:

Be it known that I, ELLIS R. BROCK, a citizen of the United States, and resident of Bamberg, in the county of Bamberg and State of South Carolina, have invented certain new and useful Improvements in Thread-Board Cleaners for Spinning-Machines, of which the following is a specification.

10 This invention relates to means for cleaning the thread board of spinning machines and is in the nature of an attachment which may be applied to machines already in use as well as to new machines. It embodies a 15 cleaning device or brush which is operated mechanically and automatically from the drive mechanism of the machine to move continuously back and forth over and in contact with the surface of the guide board 20 and the hinged thread guide extensions from one end of the guide board to the other across the machine, collecting and removing the fine lint and dust which tends to collect there. The purpose of the invention is to simplify 25 and improve the construction whereby the desired result of cleaning is secured more perfectly while at the same time the cost and trouble of manufacture, the work of installing the device on spinning machines and its 30 liability to get out of order are reduced. The novel features of construction will be apparent from the following description and claims taken in connection with the drawings.

35 In the drawings,

Figure 1 is a plan view of the thread board and thread guides of a known form of spinning machine having my invention applied thereto;

40 Fig. 2 is a vertical section taken in the direction of movement of the cleaning device, and

Fig. 3 is a cross-section on the line 3—3 of Fig. 2, but showing the operating cams 45 and clamping arms in full lines.

It has not been deemed necessary to show in the drawings many parts of the spinning machine to which my invention is applied since the structure, arrangement and operation 50 of such machines are well known and will be understood and it is necessary therefore to show only so much of the old machine as will make clear how my invention is applied to it. In the drawings 10 represents the thread board which carries along one edge the hinged members 11 provided

with the wire looped extensions 12 to receive the thread passing through the drawing rolls 13. As is well known the thread board 10 is secured to the edge of the main 60 frame 14 of the spinning machine.

My invention includes a brush 15 extending transversely across the thread board 10 and partly over the extensions 11 and provided with downwardly projecting bristles 65 16 making contact with the surface of the board and extensions and this brush or cleaning device is moved longitudinally of the board from end to end, thus removing lint and other material which may collect on the 70 surface. The means for moving the cleaning device or brush continuously in its reciprocations from one side of the machine to the other along the thread board includes an endless belt or cord 17 passing around a 75 loose pulley at one end and a pulley 19 at the other end of the thread board, the intermediate portions of the cord or belt of course being parallel and rather close together. The pulley 19 is driven through a 80 shaft 20 and bevel gears 21, 22 and a belt wheel 23 which may be connected by belt 24 to one of the rotating shafts of the spinning machine so as to constantly drive the pulley 19. Adjacent the driven pulley 19 there are 85 two loose pulleys 25 which bear on the outer margins of the belt or cord bringing them closer together than they would be if drawn straight from the pulley and a pair of similar free pulleys are placed adjacent the loose 90 pulley for the same purpose on the other side of the machine. A housing 27 preferably made of thin metal is secured to the thread board longitudinally from one side of the machine to the other and is substantially 95 rectangular in section with a slot opening 28 in the top and the cord or belt 17 passes longitudinally across the machine in this housing and is thus largely protected from fiber and dirt. This housing occupies 100 a position between the sections of bristle extending downward from the brush top portion and is thus below the brush mechanism, some of the brushing points being removed at that portion. A comparatively 105 short housing of thin metal 29 fits within the housing 27 so as to slide freely longitudinally therein and is rigidly secured to the solid member of the brush 15 by suitable means such as the T post 30. The belt or 110 cord 17 passes within this housing 29 immediately above the bottom and this housing

serves as one part of the clamping means for connecting the cleaning device or brush 15 to the belt or cord. On the upper face of the brush 15 there are two posts 31, 32 having 5 mounted therein a shaft 33 which is rotatable and which carries two cams 34 and 35 rigidly secured to it so as to turn with it. Each cam has rotary connection with the circularly bent end of the movable clamping 10 strip or member 36 and that clamping member extends from the cam downwardly at an angle through a slot 37 in the top of the brush, which slot serves as a guide. The lower end of the clamping arm 36 extends 15 through the slot 28 in the top of the housing 27 and down to a point just above the cord or belt and is there bent to form a downwardly facing bearing surface 38 adapted to bear downwardly pressing the cord against 20 the inner lower face of the housing 29 thus clamping it to the brush or cleaning device. It will be observed that there is a movable clamping arm for each side of the cord or belt and that they are inclined at different 25 angles. The cam eccentric on which these movable clamping arms are mounted are so arranged that when the greater diameter of the eccentric is approximately in line and on the same side as the clamping arm in one 30 case that arm will be pressed down into clamping position while the eccentric for the other arm will at that time have its greatest diameter out of line with its clamp- 35 ing member and thus that member will be raised from clamping position. It is of course necessary in moving the brush or cleaning device from one side of the machine to the other that it shall be clamped to one side of the cord and to make it automatically 40 stop and start a reverse movement back to the other side of the machine, it is necessary to release the clamp on one side and apply that on the other side. In my device this is done by means of the extensions 39, 40 rigidly secured to the eccentric or the shaft 45 and so arranged that the one on the forward side of movement will be in substantially a horizontal position and will strike an inclined abutment 41 as the brush reaches one 50 end of the thread board and this abutment will raise the arm 39 turning the two eccen- trics releasing one clamp and applying the other automatically. In the drawings I have shown this abutment for effecting the 55 reverse in the clamps only at the driving end of the thread board, but it will be understood that there is a similar arrangement at the other end.

Having thus described my invention what 60 is claimed as new and desired to be secured by Letters Patent is:

1. In a cleaning device for the thread boards of spinning machines the combination with an endless belt extending over said 65 thread board from one side of the machine to

the other, means for driving said belt, a cleaning device adapted to move along and in contact with said board, means carried by said cleaning device for alternately clamping it to the oppositely moving portions of the belt embodying an element having a fixed relation to said cleaning device and an element movable thereon between which elements the belt is clamped and trips at the ends of the thread board operating by 75 contact to so move the movable elements of the clamping means on said cleaning device as to disengage one portion of the belt and engage the other portion for the reverse movement of the cleaning device. 80

2. In a cleaning device for the thread boards of spinning machines the combination with an endless belt extending over said thread board from one side of the machine to the other, means for driving said belt, a cleaning device adapted to move along and in contact with said board, clamping means carried by said cleaning device embodying a rigidly secured member close along the belt on the side opposite the cleaning mem- 90 ber and two movable members having bearing surfaces adjacent the two sides of the belt opposite the rigid member and adapted to alternately press the belt against said rigid member thus clamping it to the clean- 95 ing device. 100

3. In a cleaning device for the thread boards of spinning machines the combination with an endless belt extending over said thread board from one side of the machine to the other, means for driving said belt, a cleaning device adapted to move along and in contact with said board, clamping means carried by said cleaning device embodying a rigidly secured member close along the belt 105 on the side opposite the cleaning member and two movable members having bearing surfaces adjacent the two sides of the belt opposite the rigid member and adapted to alternately press the belt against said rigid mem- 110 ber thus clamping it to the cleaning device and automatic means for causing one movable member to release and the other to engage the belt as the cleaning device reaches the end of the thread board. 115

4. In a cleaning device for the thread boards of spinning machines the combination with an endless belt extending over said thread board from one side of the machine to the other, means for driving said belt, a cleaning device adapted to move along and in contact with said board, clamping means carried by said cleaning device embodying a rigidly secured member close along the belt on the side opposite the cleaning mem- 120 ber and two movable members having bearing surfaces adjacent the two sides of the belt opposite the rigid member and adapted to alternately press the belt against said rigid member thus clamping it to the clean- 125 130

ing device, twin cams connected together and carried by the cleaning device for simultaneously moving the movable members one into clamping position and one out of 5 clamping position, and means including a projecting member connected to the cams and a fixed contact member for turning the cams to shift the clamp.

5. In a cleaning device for the thread 10 boards of spinning machines the combination with an endless belt extending over and close to said thread board from one end to the other, means for driving said belt, a cleaning device over said belt in the form of 15 a brush with bristles extending downwardly into contact with the thread board on both sides of said belt, means for alternately clamping said brush to opposite sides of said belt to cause its reciprocation over the thread 20 board and automatic means for shifting the clamp at the end of the board to cause reverse movement.

6. In a cleaning device for the thread

boards of spinning machines the combination with an endless belt extending over and 25 close to said thread board from one end to the other, means for driving said belt, a cleaning device over said belt in the form of a brush with bristles extending downwardly into contact with the thread board on 30 both sides of said belt, a housing on said thread board around said belt under said brush provided with a slot in its top extending from end to end of said thread board, a clamping member below said belt in 35 said housing and having fixed connection through said slot to said cleaning device to move therewith, two automatically movable clamping members carried by said device extending through said slot with bearing surfaces over the two sides of said belt and 40 means near the ends of the thread board for automatically shifting the clamping action from one side of the belt to the other.

In testimony whereof I affix my signature. 45

ELLIS R. BROCK.
